(57) **CLAIM**

The ornamental design for a combination stapler/tape dispenser, as shown and described.

DESCRIPTION

FIG. 1 is a perspective view of the combination stapler/tape dispenser showing top, front, and left side of our new design; FIG. 2 is a perspective view of the combination stapler/tape dispenser showing top, rear, and left side of our new design; FIG. 3 is a perspective view of the combination stapler/tape dispenser showing top, rear, and right side of our new design, wherein a storage compartment is opened; FIG. 4 is a perspective view of the combination stapler/tape dispenser showing the front and left side of our new design, wherein a stapler portion is raised; FIG. 5 is a left side view of the combination stapler/tape dispenser of FIG. 1, the right side view being a mirror image; FIG. 6 is a top view of the combination stapler/tape dispenser of FIG. 1; FIG. 7 is a bottom view of the combination stapler/tape dispenser of FIG. 1; FIG. 8 is a front view of the combination stapler/tape dispenser of FIG. 1; and, FIG. 9 is a rear view of the combination stapler/tape dispenser of FIG. 1. Broken lines showing a roll of tape are for illustrative purposes only and form no part of the claimed design.
